UNITED STATES PATENT OFFICE

2,069,730

FLUID CONTROL FOR DUPLICATORS

Frederick W. Storck, Arlington, and Carl V. Franson, Dorchester, Mass., assignors to Standard Mailing Machines Company, Everett, Mass., a corporation of Massachusetts

Application April 5, 1935, Serial No. 14,804

10 Claims. (CL. 137—68)

This invention relates to improvements in duplicating machines wherein the record copy or master sheet is made in reverse with suitable copying ink and reproduced therefrom on sheets of paper, or the like, having a moistened face; and the invention relates more particularly to a fluid control and shut-off for a fluid supply reservoir and intermediate tank adapted to be used in connection with duplicating machines of this character.

In a duplicating machine of the above referred to character and such as is shown and described in our United States Letters Patent Nos. 1,964,933, issued July 3, 1934, and 1,988,056, issued January 15, 1935, the clear sheet to be printed upon is moistened with a film of volatile, quickly diffusing liquid. In our preferred form, this fluid is supplied from an air-locked reservoir to an intermediate, barometrically controlled tank adapted to maintain a predetermined level of fluid therein and from which it is subsequently applied to the clear sheet. Such an intermediate tank and one method of applying the fluid to a clear sheet is shown and described in our co-pending application, Serial No. 9,151.

In utilizing volatile liquid for the above purpose it is obvious that the liquid contained in the intermediate tank is subject to evaporation when the machine is idle. Over an extended period of time this evaporation would wastefully consume the contents of the reservoir from which the intermediate tank is supplied.

Therefore, the primary object of our present invention is to provide a simple and effective fluid level control and shut-off formed of integral or connected parts of the fluid reservoir and intermediate tank without the necessity of employing additional parts or valves.

Another object is to provide an air-locked supply reservoir that may be readily removed for refilling and which, when in operative position, will coact with the intermediate tank or connections thereto to form a fluid level control and shut-off.

A further object is to so construct our fluid level control whereby a simple movement of the reservoir will position the discharge orifice of the reservoir in converse operative and inoperative discharging positions relative to the intermediate tank.

With the above and other objects in view our invention comprises a novel combination and arrangement of parts hereinafter described and more specifically pointed out in the appended claims. In the accompanying drawings we have

shown a preferred form of our fluid control, together with modifications thereof sufficient to enable those skilled in the art to understand the construction and operation thereof.

Referring to the drawings:

Fig. 1 is a vertical section of our fluid reservoir and a portion of an intermediate tank and having a preferred form of our fluid control embodied therewith; in this view the fluid control is in its open position.

Fig. 2 is a view corresponding substantially to Fig. 1, but shows the fluid control in a closed position.

Fig. 3 is a sectional view taken along line 3—3, Fig. 1.

Fig. 4 is a sectional view taken along line 4—4, Fig. 2.

Fig. 5 is a view corresponding substantially to Fig. 1, but shows a modification of our fluid control; in this view the fluid control is shown in its closed position.

Fig. 6 is a view corresponding substantially to Fig. 5, but shows the fluid control in its open position.

Fig. 7 is a sectional view taken along line 7—7, Fig. 5.

Fig. 8 is a sectional view taken along line 8—8, Fig. 6.

Fig. 9 is a vertical section corresponding substantially to Fig. 1, but shows another modification of our fluid control; in this view the fluid control is shown in its closed position.

Fig. 10 is a view corresponding substantially to Fig. 9, but shows the fluid control in its open position.

Fig. 11 is a sectional view taken along line 11—11, Fig. 9.

Fig. 12 is a sectional view taken along line 12—12, Fig. 9.

Fig. 13 is a sectional view taken along line 13—13, Fig. 10.

The intermediate fluid tank 10 illustrated is provided, adjacent its top, with a longitudinal slot in which the capillary feed wick 11 and its backing plate 12 are frictionally disposed. In this instance the tank 10 is provided with a projecting conduit 13, the outer end of which is secured to a reservoir support 14.

The reservoir support 14 is provided with a longitudinal chamber 14a which is disposed with a substantially vertical axis and connects, by means of a communicating opening 14b, with the orifice 13a of the tank conduit 13. The upper portion 14c of the reservoir support 14 is enlarged to form an annular rim face 14d. The expression

"substantially vertical axis" is to be construed to include any position above a horizontal plane.

In this instance the supply reservoir is adapted to be air-locked and comprises a body portion 15, preferably of a transparent character, secured between opposed end plates 16, 17 by means of tie rods 18. One end plate 16 is provided with a spout or conduit 19 which is adapted to freely engage in the longitudinal chamber 14a of the reservoir support 14. In our preferred form, as illustrated at Figs. 1 and 2, the side wall of the conduit 19 is provided with an opening 19a adapted for registration with the communicating opening 14b and conduit orifice 13a. The level of liquid in the tank is controlled by the position of the opening 19a and its relation to the bottom of the intermediate tank. The fluid is supplied to the intermediate tank 10 from the air-locked reservoir and thus the fluid supply level in the tank 10 is barometrically controlled, as is well known.

The areas of the orifice or discharge opening 19a and conduits are governed by the characteristics and surface tension of the fluid as is well known in the art of barometric fluid feeds of this character.

In operation, when the reservoir is removed from its support 14, the conduit 19 is withdrawn from its chamber 14a. The reservoir is then inverted with the conduit in an upright position and through which the operator replenishes and fills the reservoir with fluid. After the reservoir has been filled, the operator engages the conduit 19 with the annular rim face 14d of the reservoir support and quickly inverts the reservoir and, with the conduit 19 depending, the bell-shaped portion 14c guides the conduit 19 into its engaging position in its chamber 14a. The end plate of the reservoir engages the annular rim face 14d and axially positions the discharge opening 19a relative to the tank conduit 13.

During this replacing of the reservoir it is obvious that some flow of the liquid from the conduit would take place; therefore, the upper portion 14c of my support has an enlarged substantially bell-shaped chamber coincident with the conduit chamber 14a. This also facilitates replacing the conduit in its chamber 14a with a minimum amount of spill, as any discharge from the reservoir, during the replacing operation, will be directed into the intermediate tank 10.

Our reservoir may be provided with means (not shown), such as an arrow or similar mark attached thereto, for indicating the position of the discharge opening 19a relative to its registering position with the conduit 13.

The reservoir is rotated in its axial position, in either direction, until the reservoir discharge opening 19a registers with the communicating opening 14b, see Fig. 1. This permits a clear passage for the fluid to be discharged from the reservoir to the intermediate tank 10. As the fluid in the tank 10 rises to the top level of the discharge opening 19a, a seal is formed and the reservoir becomes air-locked, thus preventing further discharge therefrom.

When the level of the fluid in the tank 10 is diminished below the sealing point and sufficient to break the surface tension of the fluid, air passes into the reservoir, as is well known, and permits replenishment of the fluid to the tank 10.

When the device is to remain idle for a period of time, the operator simply rotates the reservoir, in either direction, until the discharge opening 19a of the reservoir is in a non-registering position, see Fig. 2. This retains the fluid within

the reservoir and eliminates evaporation of this fluid, while the fluid remaining in the tank 10 and conduit 13 is subjected to evaporation.

To start operations, the operator simply rotates the reservoir until the discharge opening 19a again registers with the conduit 13 and the tank 10 is thus supplied with its required fluid as above described.

At Fig. 5 we have shown a modification of our device wherein the reservoir discharge conduit 20 is of sufficient length to obstruct the communicating opening 14b and prevent discharge therethrough when the end plate 16 of the reservoir is positioned in engagement with the annular rim face 14d. In this modification the end plate 16 is provided with a cam lug 16a adapted to engage in a cam recess 14e, formed contingent with the annular rim face 14d, when the opening 14b is obstructed.

As the reservoir is rotated in its axial position, the lug 16a engages the side cam faces of the recess 14e and elevates the reservoir to a point where the end face of the lug engages the annular rim face 14d. This elevation of the reservoir positions the discharge opening 20a, of the reservoir conduit 20, in a discharging registration with the communicating opening 14b and permits a clear passage for the fluid from the supply reservoir to the intermediate tank 10, see Fig. 6.

In this modification, shown at Fig. 5, the fluid level in the intermediate tank 10 is controlled by the position of the conduit orifice 13a relative to the bottom of the intermediate tank 10.

A further modification of our fluid control and shut-off is shown at Fig. 9. In this particular instance the rim face 14d is provided with a detent notch 14f adapted to receive a detent pin 16b, which is secured to the end plate 16 of the reservoir, when the end plate 16 is in engaging position with the annular rim face 14d. The reservoir discharge spout 21 in this modification is also of a sufficient length to obstruct the communicating opening 14b as described in our first modification.

At Fig. 9 the device is shown in its closed position. To open the fluid passage to the tank the reservoir is vertically lifted and partially rotated in its axial position and the end face of the detent pin 16b positioned in engagement with the annular rim face 14d. To close the fluid conduit 50 registers with its opening 14f, which permits the reservoir to again move downwardly to its closed position.

Having thus described our invention in a preferred form with modifications therein, it is obvious that other modifications may be accomplished without departing from the spirit and scope of our invention, but what we claim is:—

1. A barometrically controlled fluid supply for duplicators having a supply reservoir with a discharge conduit, a chamber having a substantially vertical axis and adapted to receive said discharge conduit in a manner whereby said conduit may be freely removed and replaced, a discharge opening from said chamber, and means for alternately positioning an aperture of said discharge conduit in registering and non-registering positions relative to said chamber discharge opening, said means being operative upon rotation of said reservoir in its normal, substantially vertical, axial position.

2. A barometrically controlled fluid supply for duplicators having a reservoir with a tubular discharge conduit, substantially forming an integral

part of said reservoir, a chamber having a substantially vertical axis and adapted to receive said discharge conduit in a manner whereby said conduit may be freely removed and replaced, 5
5 guide means associated with said conduit chamber and whereby the advance end of said conduit is directed into said chamber, a discharge opening from said chamber with means for conversely positioning said discharge conduit relative to said 10
10 chamber opening, said means being operative upon rotation of said reservoir in its normal, substantially vertical, axial position.

3. A fluid supply for duplicators having a normally air-locked reservoir with a discharge conduit integral therewith, a support for said reservoir, a chamber within said support having a substantially vertical axis and adapted to freely engage said discharge conduit in a manner whereby said conduit may be freely removed and 15
15 replaced, a container adapted to maintain a predetermined level of fluid therein, a conduit connection disposed between said container and chamber; means disposed between said support and reservoir whereby said reservoir conduit may 20
20 be positioned relative to the chamber opening of said conduit connection, said means being operative upon rotation of said reservoir in its normal, substantially vertical, axial position.

4. A fluid supply for duplicators having a container adapted to maintain a predetermined level of fluid therein, a conduit for said container, a fitting for said conduit having a chamber disposed with a substantially vertical axis, a communicating opening disposed between said chamber and said conduit and a substantially cone-shaped portion adjacent said chamber, a reservoir having a tubular discharge conduit connected therewith and adapted to be guided and positioned for movement within said chamber to 25

obstruct said communicating opening with means to position said reservoir discharge conduit to effect a continuous orifice between said container and reservoir, said means being operative upon rotation of said reservoir in its normal, substantially vertical, axial position and said conduit.

5. A fluid supply for duplicators having a container adapted to maintain a predetermined level of fluid therein, a conduit for said container, a fitting having a chamber with a communicating opening to said conduit, a removable reservoir supported by said fitting, said reservoir having a discharge conduit secured thereto which is adapted for movement within said chamber, a detent pin secured to said reservoir; an annulus forming a part of said support and having a detent opening whereby said detent pin is engaged by said annulus and opening to position the discharge orifice of said reservoir conduit relative to said chamber opening.

6. A fluid supply for duplicators having a container adapted to maintain a predetermined level of fluid therein, a conduit for said container, a fitting having a chamber disposed with a substantially vertical axis and with a communicating opening to said conduit, a removable reservoir supported by said fitting, said reservoir having a tubular discharge conduit secured thereto which is adapted for movement within

said chamber, a projecting cam secured to said reservoir; an annulus forming a part of said support, a cam portion contiguous with said annulus and adapted to be engaged by said projecting cam whereby the discharge orifice of said reservoir conduit is positioned relative to said communicating opening upon rotation of said reservoir in its normal axial position. 5

7. A fluid supply for duplicators having a container adapted to maintain a predetermined level of fluid therein, a chamber associated with said container and having a communicating opening therewith; a removable reservoir rotatably supported relative to said chamber, a spout secured to said reservoir and adapted to freely engage in said chamber, a discharge orifice in said spout adapted to be rotatively positioned for registration and non-registration with said communicating opening.

8. A fluid supply, for duplicators, having a removable fluid supply reservoir with a tubular conduit forming substantially a part thereof, said reservoir and conduit, when in operative position, being disposed with a substantially vertical axis of rotation, a barometrically controlled container 20

being disposed with a substantially vertical longitudinal axis of rotation; a container, a chamber arranged closely and slidably to embrace said spout and provided with a discharge opening connected with said container, said spout being provided with a discharge opening whereby fluid therein may flow from said reservoir through said discharge opening of said chamber when said spout is in one position and means operable through the rotation of said reservoir about its longitudinal axis to change the position of said spout and thereby to cause a portion of said spout to close said discharge opening of said chamber.

10. A fluid supply for duplicators having a removable fluid supply reservoir with a conduit extending therefrom, said reservoir and conduit being operatively disposed with a substantially vertical axis of rotation; a barometrically controlled container for receiving fluid from said reservoir, said conduit, when in operative position, forming 60
